UNITED STATES PATENT OFFICE

FREDERICK J. HERTER, OF EAST CLEVELAND, OHIO, ASSIGNOR TO CAMEL COMPANY,
OF CHICAGO, ILLINOIS, A CORPORATION OF ILLINOIS

CAR DOOR

Application filed December 9, 1929. Serial No. 412,596.

This invention relates to a car door and more particularly to a door for stock cars and concerns itself with a door having one or more auxiliary doors for loading and unloading a double deck stock car.

The invention comprises the novel structure and combination of parts hereinafter described and more particularly pointed out and defined in the appended claims.

10 In the accompanying drawings which illustrate a preferred form of this invention and in which similar reference numerals refer to similar features in the different views.

15 Figure 1 is a fragmentary side elevational view of a stock car containing a door involving this invention.

Figure 2 is a view similar to Figure 1 but showing the door in open position and the auxiliary door in closed position.

20 Figure 3 is an enlarged fragmentary sectional view taken upon the line III—III of Figure 1 looking in the direction of the arrows.

25 Figure 4 is an enlarged fragmentary sectional view taken upon the line IV—IV of Figure 1 looking in the direction of the arrows.

30 Figure 5 is an enlarged fragmentary sectional view taken upon the line V—V of Figure 1 looking in the direction of the arrows.

Figure 6 is an enlarged sectional view taken upon the line VI—VI of Figure 2.

35 Figure 7 is an enlarged sectional view taken upon the line VII—VII of Figure 1.

Figures 8, 9 and 10 are enlarged fragmentary detail views illustrating modified forms of guides for the auxiliary door.

40 Figure 11 is a fragmentary sectional view taken upon the line XI—XI of Figure 12.

45 Figure 12 is an enlarged fragmentary elevational view of the latching means for the auxiliary door.

Figure 13 is a fragmentary side elevational view of a stock car illustrating a modified form of the invention.

In the drawings there is shown a door 1 for a stock car and those parts of the stock car which are adjacent the door. The door comprises a metal frame consisting of a front

50 Z bar 2 and a rear angle bar 2^a, a top Z bar

3 which has its web resting upon the top of the door and a guide flange 3^a (Figure 3) extending inside of the depending flange of a track 4, and a lower Z bar 5 which has a depending flange 5^a (Figure 4). These frame 55 members are suitably connected together by gusset plates 6 to provide a rigid rectangular frame. The Z bars 3 and 5 are connected by an intermediate brace or strut 7. Spaced horizontal slats 8 are bolted or secured to 60 the lateral frame members 2, 2^a and strut 7.

The door is supported upon the track 4 by means of rollers 9 journaled in suitable hangers 10 secured to the upper portion of the door as is well known in the art. In order to 65 guide and maintain the lower edge of the door from swinging outwardly too far, a guide rod 11 is attached to the sill of the car and a closed link 12 secured to the depending flange 5^a encircles said rod. 70

The stock car shown is of the double deck type. The floor of the upper deck is indicated at 13 (Figure 2). When the upper deck has been loaded with live stock or other lading, it is necessary and desirable to prevent the 75 same from escaping while the lower deck is being loaded. To this end, the main door 1 has been provided with an auxiliary door 14 (Figure 2) which moves relative to the main door so that it can be moved to act as 80 a barrier for the upper deck to prevent the escape of the lading.

In the present instance, the auxiliary door 14 is mounted for sliding movements relative to the main door so that it can be slid across 85 the upper deck when the main door is open as shown in Figure 2. For this purpose, the main door is provided with open space 15 above the floor of the upper deck for the auxiliary door. It will be noted that this 90 open space is bounded at its upper and lower limits by the transverse double channel like guides 16 (Figure 5). It will be noted that each double channel guide has a channel 16^a for receiving a slat 8 of the door and a 95 channel 16^b for receiving an edge of the auxiliary door. The channels 16^b face each other and form a slideway for the auxiliary door.

Instead of the double channel guides, the modifications shown in Figures 8, 9 and 10 100

may be used. In Figure 8 there is shown a construction in which a pair of plates 17 are adapted to be bolted to a slat 8 and projecting therebeyond to form a guide channel for the 5 auxiliary door 14. In Figure 9, one plate 17 is used and a strip 18 is attached to the edge of the slat 8 for cooperating with the plate 17 to form a guideway for the auxiliary door. The strip 18 and the longitudinal edge of the 10 auxiliary door have interfitting rabbeted edges as shown. In Figure 10, a Z bar 19 is shown attached to the slats adjacent the auxiliary door opening. The web of the Z bar extends over the edge of the slat 8 with 15 one flange attached to the slat 8 and the other extending into the auxiliary door opening. A plate 17 is attached to the strip 8 in opposed relation to the last mentioned flange of the Z bar 19 to form a channel like guideway for 20 receiving the edge of the auxiliary door.

The auxiliary sliding door 14 consists of a rear U shaped metal frame member 20 and a pair of front plates 21 (Figure 6). Wooden slats 22 connect the rear frame member 20 and the plates 21 which extend in parallel relation. The outer plate 21 is outwardly offset to increase the distance therebetween for receiving the slats. The upper and lower slats 22 are preferably bevelled or tapered as 25 shown in Figure 5 to facilitate the sliding movements of the auxiliary door. The in-turned flange of the front Z bar 2 upon the main door is cut away at the auxiliary door as indicated at 23 (Figure 6) to allow the 30 auxiliary door to pass. However when the auxiliary door has been projected as shown in Figure 2, the rear end will be behind the front Z bar 2 as shown in Figure 6 and will be restrained from outward movement, while 35 the front end will be latched to the front door post 24 in a manner that will now be set forth.

Between the forward ends of the plates 21, there is a latch hook 25 which is provided with a slot 26 through which a pivot 27 passes.

40 The pivot is in the form of a rivet that passes through the plates 21. This latch hook 25 is designed to extend through a slot 28 in the front door post and come into latching engagement with the bottom of such slot so that the auxiliary door will be held against 45 sliding movement and also against outward movement at its front end so the main door can be opened while the auxiliary door remains latched or anchored to the front post.

50 While only one latch hook has been illustrated it will be understood that several may be used if desirable. The latch hook 25 may be readily swung upwardly and out of engagement with the slot 28 and into the position shown in Figure 12 in which position the latch has dropped down bringing the upper end of the slot into engagement with the pivot so that the latch hook may be moved 55 through a smaller arc when swung to its operative position through the slot 28, and

may be extended at the same time due to the slot 26.

In order to latch the main door in its closed position, a hinge support 29 is attached to each door post as shown in Figure 7 and a latch member 30 is hinged to each support 29 so as to be swung over the outer surface of the door. Each latch member is provided with a slot 31 for receiving hasps 32 upon the door. Each latch member also has an integral hasp 32^a. 75 A chain 33 is anchored to the door above each pair of hasps 32 and 32^a and the lower end of each chain carries a fork 34 for extending through the hasps. The outstanding flange of the front Z bar 2 is cut away as indicated 80 at 35 in Figure 7 to allow the front latch member to swing flat against the door.

In Figure 13, a modified stock car door 1^a is shown. The parts of this modified door are substantially the same as the preferred 25 form and principally differs therefrom in the use of two auxiliary doors 14, one for the upper deck and one for the lower deck.

It will be apparent that it becomes a simple matter to load a double deck car according to this invention, especially when it is loaded with live stock. According to this invention the main door is opened and the upper deck is loaded, then the auxiliary door is moved over the upper deck and latched to 90 act as a barrier. The lower deck may then be loaded and thereafter the main door may be slid to closed position and latched as previously set forth. When two auxiliary doors are used as shown in Figure 13, either the upper or lower deck may be first loaded as is 95 readily apparent.

I am aware that many changes may be made and numerous details of construction may be varied through a wide range without departing from the principles of this invention, and I therefore do not purpose limiting the patent granted hereon otherwise than necessitated by the prior art.

110 I claim as my invention:

1. In a stock car having a door opening and an upper deck and a lower deck, a sliding door mounted upon said car for closing said opening, said door having spaced guides opposite one deck forming guideways, an auxiliary door slidingly mounted in said guideway, a slotted post at the front of said doorway and a latch on said auxiliary door engageable in the slot in said post for latching said auxiliary door thereto while said main door is 115 opened for access to the lower deck.

2. In a double deck stock car having a door opening, a sliding door mounted upon said car for closing said opening, said door having opposed channels opposite one deck forming a guideway therebetween, an auxiliary door consisting of spaced members secured in rigid relation slidingly mounted in said guideway, a front door post, and means for anchoring said auxiliary door to said door post while 120 125 130

said main door is being opened for access to the lower deck.

3. In a double deck stock car having a door opening, a sliding door mounted upon said car for closing said opening, said door having lateral vertical metal strips, and opposed members opposite one deck, having grooves in their confronting edges forming a guideway, an auxiliary door slidably mounted in 10 said guideway, a slotted door post at the front end of said door opening, a latch upon said auxiliary door extending through said slot for anchoring said auxiliary door to said post when said main door is opened, the rear 15 end of said auxiliary door engaging behind the front lateral strip when said main door is open.

4. In a double deck stock car having a doorway, a sliding door mounted upon the 20 car for closing said door way, said door having spaced guide members opposite one deck, an auxiliary door slidably mounted between said guide members, a front door post, means for anchoring said auxiliary door to said door 25 post and a vertical strip upon the main door for confining the rear end of said auxiliary door when said main door is open.

5. In a double deck stock car having a door

30

way, a sliding door mounted upon said car for closing said door way, said door having spaced guides opposite one deck, an auxiliary door slidably mounted between said guides for closing such deck when said door is open 70 for access to the other deck and means for anchoring said auxiliary door to said car.

6. In a double deck stock car having a door way, a sliding door mounted upon said car for closing said door way, said door having 75 spaced guides, an auxiliary door mounted between guides and having its upper and lower edges slidably engaging said guides for closing a part of said door way when the main door is open and means for anchoring said auxiliary door to said car. 80

7. In a double deck stock car having a door way, a sliding door mounted upon said car for closing said door way, said door having spaced guides in the plane of the door, an auxiliary door slidably mounted between said guides and normally constituting a portion of said door, said auxiliary door being adapted for projection for closing the upper deck when said main door is in its open position 90 for access to the lower deck and means for latching said auxiliary door in such position. 95
